BOTTLE CAPPING DEVICE

Filed April 8, 1922

Fig. 5.

UNITED STATES PATENT OFFICE.

RICHARD E. MEYER, OF DETROIT, MICHIGAN.

BOTTLE-CAPPING DEVICE.

Application filed April 8, 1922. Serial No. 550,634.

To all whom it may concern:

Be it known that I, RICHARD E. MEYER, a citizen of the United States of America, residing at Detroit, in the county of Wayne 5 and State of Michigan, have invented certain new and useful Improvements in Bottle-Capping Devices, of which the following is a specification, reference being had therein to the accompanying drawings.

This invention relates to a bottle capping device and my invention aims to provide a portable hand operated tool by which a cap may be securely mounted on the mouth of a bottle or similar receptacle, the tool being designed for holding and fixing a metallic cap, preferably of the crimped configuration, on the mouth of the bottle, so that the bottle mouth will be sealed.

My invention further aims to provide a bottle capping tool embodying means for temporarily holding the cap, means for gripping the bottle neck, and means for forcibly clamping the temporarily held cap on the mouth of the bottle, all of said means being compactly assembled into a tool that may be carried in the pocket, in contradistinction to stands and such capping devices that must be placed on a table, wall or other support.

The construction entering into my capping device will be hereinafter specifically described and then claimed, and reference will now be had to the drawing wherein

Figure 1 is a longitudinal sectional view of the bottle capping device, showing a cap on a portion of a bottle neck about to be fixed thereon;

Fig. 2 is a horizontal sectional view taken on the line II—II of Fig. 1;

Fig. 3 is a bottom plan of the device;

Fig. 4 is a horizontal sectional view taken on the line IV—IV of Fig. 1;

Fig. 5 is a longitudinal sectional view taken on the line V—V of Fig. 1, and

Fig. 6 is a view similar to Fig. 1, showing the cap fixed on the bottle neck.

In the drawing, the reference numeral 1 denotes a portion of a bottle neck having a head 2 and a lip 3, and adapted to be seated on the lip 3 to close and seal the bottle neck 1 is a metallic cap 4 provided with a washer 5 and a crimped edge 6. This cap is of a conventional form adapted to have its crimped edge closed about the lip 3 with

the washer 5 more or less compressed, as shown in Fig. 6.

The cap manipulating tool comprises a tubular body 7 and slidably in said tubular body is a hollow plunger 8 containing an axial yieldable stem 9, which has its upper end provided with a transverse pin or stop 10. The lower end of the stem 9 is provided with a head 11 within an inverted cup shaped crimping member 12, carried by the lower end of the plunger 8. Encircling the stem 9, between the upper end of the plunger 8 and the head 11 is a coiled expansion spring 13 which holds the stem 9 with the transverse pin 10 thereof normally in engagement with the upper end of the plunger 8, but permits of the stem 9 and its head 11 receding under excessive pressure. The member 12 does not exactly crimp the cap 4 but it is adapted to deflect the crimped edges 6 of the cap inwardly about the lip 3, as said cap is retained on the bottle neck by the head 11 of the stem 9, with the member 12 moving downwardly towards the head 2 of the bottle neck, as shown in Fig. 6. The stem 9 may remain stationary while the plunger 8 is depressed, and this is brought about by a pivoted lever 14 being movable relative to a stationary lever 15, the levers 14 and 15 constituting handles by which the tool may be manipulated. The stationary lever 15 has a lug 16 extending through a slot 17 in an annular flange 18 of the tubular body 7, and said lever or handle is connected to the tubular body by a screw 19 or other fastening means. The lever or handle 14 is more or less channel shaped so that its fastened end may be braced by the tubular body 7 and an upstanding lug 20 of said body.

The pivoted lever or handle 14 is somewhat channel shaped and is pivotally mounted by a pin 21 between apertured lugs 22 carried by the tubular body 7, said lever or handle having a projection 23 extending on to the upper end of the plunger 8 for depressing said plunger when the lever or handle 14 is swung towards the stationary lever or handle 15, as shown in Fig. 6.

The flange 18 of the tubular body 7 has enlargements to which are connected opposed resilient cap holding arms 24 adapted to temporarily hold the cap 4 relative to the member 12, the cap being placed in en-

gagement with the opposed arms 24, as shown in Fig. 5, so that the tool may be placed down over the head 2 of the bottle neck. The resilient cap holding arms 24 may be held by screws 24^a having large heads or projections which will afford stops for the purpose that will hereinafter appear.

The tubular body 7 has a plurality of radially disposed enlargements 25 providing sets of apertured lugs 26 and pivotally mounted between said lugs, by pins 27 are the apertured ends of bottle gripping arms 28, said arms having the lower ends thereof provided with shoulders 29 and gripping members 30. The gripping members 30 are disposed at an angle to engage under the head 2, as shown in Figs. 1 and 2, and by reference to Fig. 3, it will be noted that the segment members are somewhat segment shaped at the inner edges thereof so that said gripping members will fit about the bottle neck and grip a considerable portion thereof, in contradistinction to a three-point engagement. It will be practically impossible for the gripping members to slip and such engagement with the bottle neck is maintained by a collar 31 loosely supported about the tubular body and the arms 28, said collar having its inner wall engaged by the outer edges of the arms 28 and the shoulders 29 of said arms and the heads of the screws 24^a will prevent the collar from becoming accidentally displaced. The collar 31 simply embraces the arms 28 to hold said arms against the head 2, and the angularity of the outer edges of the arms 28 is not sufficient to wedge the collar 31 upwardly as a cap is applied to the bottle. The angularity of the outer edges of the arms 28 will permit of the collar engaging the arms at different places so that the gripping members 30 may engage under the heads 2 of various diameters. When the tool is placed down over the head 2 of the bottle neck 1, the arms 28 assume a gripping position by gravity and the collar 31 will hold said arms so that the lever or handle 14 may be shifted towards the lever or handle 15 to depress the plunger 8. The cap clenching member 12 will spread the arms 24 apart, release the cap 4 and permit of the head 11 holding the cap on the lip 3 while the member 12 bends the gripped edges 6 of the cap under the lip 3 of the head 2. By manually raising the collar 31 the bottle gripping arms 28 will be released and the tool may be removed from the bottle neck. The bottle gripping arms are ordinarily hung by gravity with sufficient freedom to slip down over the neck of the bottle when the collar 31 is held in the hand placing the capping device in position, and when the collar is released it will drop on to the bottle gripping arms and clamp said arms against the

bottle neck without any excessive pressure. It is not necessary to place the bottle on a support in order to use the capping device, as the collar can be held in one hand while the neck of the bottle is inserted between the gripping arms with the other hand, the bottle neck being automatically gripped so that the bottle may be released and upon gripping the levers or handles of the device the collar may be released. The bottle is therefore not subjected to any great pressure, as though on a support, and the device can be safely used.

From the foregoing it will be observed that the cap 4 can be easily placed in the tool and temporarily held while the tool is placed over the bottle neck, and then by a single operation the cap is sealed on the bottle neck. This is accomplished without injury to the bottle and the yieldable stem 9 prevents excessive pressure from carrying the member 12 into engagement with the head 2.

While in the drawing there is illustrated a preferred embodiment of my invention, it is to be understood that the structural elements are susceptible to such variations and modifications as fall within the scope of the appended claims.

What I claim is:—

1. A bottle capping device comprising a tubular body, means carried thereby adapted for temporarily holding a cap, a plunger in said body adapted to release a cap held by said means and fix said cap on a bottle neck, a handle carried by said body, a lever supported by said body and movable towards said handle to actuate said plunger, and means carried by said body and including a loosely supported collar adapted for clamping said device relative to a bottle neck.

2. A bottle capping device comprising a body, a plunger in said body adapted to clamp a cap on a bottle neck, cap holding means carried by said body about said plunger adapted to temporarily retain a cap in engagement with said plunger, plunger actuating means carried by said body and movable towards the axis of said plunger to depress said plunger, arms pivotally connected to said body, and a collar loose about said arms adapted to cause said arms to grip a bottle neck to hold said device relative to said bottle neck.

3. A hand supported bottle capping device comprising a body, a handle on said body by which said body may be held, a plunger in said body adapted to shape a cap about a bottle neck, means carried by said body about said plunger adapted to temporarily hold the cap relative to said plunger, said means being actuated by said plunger to release said cap when in engagement with the bottle neck and shape said

cap about the bottle neck, said means including a stem in said plunger, means in said plunger for yieldably holding said stem, and plunger actuating means on said 5 body movable to and from said handle.

4. A bottle capping device comprising a body, a plunger in said body adapted to clamp a cap on a bottle neck, cap holding means carried by said body adapted to temporarily retain a cap in engagement with 10 said plunger, a handle on said body, a lever supported by said body and movable to-

wards said handle to actuate said plunger, and means carried by said body and including a loosely supported collar, adapted 15 for clamping said device relative to a bottle neck.

In testimony whereof I affix my signature in presence of two witnesses.

RICHARD E. MEYER.
